COMPONENT FOR RAILINGS, GRILL WORKS,
COLUMNS AND THE LIKE

Ellis De Loy Larson, 225 E. State Road,
Pleasant Grove, Utah 84062

Filed Mar. 1, 1971, Ser. No. 120,004

Term of patent 14 years

Int. Cl. D25—02

U.S. Cl. D13—1

FIG. 1 is a perspective view, illustrating my component design;

FIG. 2 is an enlarged front elevation thereof, the rear elevation of such component being identical;

FIG. 3 is an enlarged left side elevation thereof, the right side elevation of same being identical; and

FIG. 4 is an enlargement of a top plan thereof, the bottom plan of such component being identical.

I claim:

The ornamental design of a component for railings, grill works, columns and the like, substantially as shown and described.
